Application May 16, 1950, Serial No. 162,174

16 Claims. (Cl. 200—89)

1

This invention relates generally to electric circuit breakers, and more particularly to such circuit breakers having liquid time relay means for controlling breaker operations.

One difficulty encountered with circuit breakers having liquid time delay means for controlling operations thereof, is that gases formed by the action of the arc during circuit interruption on the arc extinguishing liquid, finds its way into the liquid delay means, such as a dashpot, and thus undesirably alters the time characteristics thereof. This difficulty is, of course, accentuated when higher current values are interrupted, because such interruptions are accompanied by the production of correspondingly greater amounts of gas.

It is, therefore, an object of the invention to provide a novel construction of hydraulically controlled circuit breaker wherein the gases formed during a circuit opening operation are prevented from interfering with the hydraulic control.

A more specific object of this invention is to provide in a hydraulically controlled circuit breaker, novel gas baffling means for preventing gases formed during a circuit opening operation from entering the hydraulic control system.

These and other objects of this invention will become more apparent upon consideration of the following detailed description of a preferred embodiment thereof, when taken in connection with the attached drawings, in which:

Figure 1 is a substantial longitudinal sectional view of a circuit breaker embodying this invention, with most of the parts within the circuit breaker casing being shown in elevation.

Fig. 2 is a partial enlarged longitudinal sectional view of the lower part of the circuit breaker mechanism shown in Fig. 1, and

Fig. 3 is a partial enlarged view of the mechanism shown in Fig. 1, with parts thereof being illustrated in section.

This invention is disclosed as being embodied in a circuit breaker of the type mounted in a container or metal tank 2 having an open top. Preferably, a cylindrical liner 4 is provided for the side wall of tank 2, with a liner disk 6 being provided for the bottom of tank 2. The liners 4 and 6 are preferably of an insulating material, such, for example, as fiber or the like. The top of tank 2 is adapted to be covered by a cover casting 8, which may be secured to the tank in any desired manner, such, for example, as by being bolted thereto (not shown). Cover casting 8 is adapted to support the circuit breaker mechanism and contacts by means of a plurality of

5 insulating supports 10 (only one shown) secured to integral lugs 12 on the cover casting, and to a casting 14. Other insulating supports 16 are adapted to support a plate 18 from casting 14 to mount a solenoid coil 20 therebetween. Still other insulating supports 22 are adapted to support the top cap 24 of an interrupter chamber 26 from cover 8.

10 The interrupter chamber 26 which is more clearly illustrated in Fig. 2 includes a cylinder 28 of insulating material, such as fiber, having threaded ends, one of which is threaded into top cap 24, and the other end of which is threaded into a bottom cap 30. The bottom cap 30 of the interrupter chamber 26 has a centrally located tapped opening for receiving a contact supporting screw 32 having a contact head 34 on the inner end thereof, and adapted to have a nut 36 on the outer end thereof for securing a conductor 38 thereto.

20 The conductor 38 leads from contact screw 32 to a conductor located in one terminal bushing 40 secured to cover casting 8, as by bolts 42. A movable contact rod 44 has the lower end thereof extending through a central opening in top cap 24 of the interrupting chamber, and is provided with a tubular sheath 46 of insulating material, such as fiber or a molded insulating material at the point where it passes through top cap 24. The lower end of contact rod 44 has a contact head 48 threaded into a hole tapped in the lower end of contact rod 44, with the contact head having a contact tip 50 secured thereto for engagement with the contact tip 34 on stationary contact screw 32 at the closed circuit position.

25 Within interrupting chamber 26 there is also provided a liquid directing structure mounted on the lower end of contact rod 44, with this structure comprising a top plate 52 having a central opening slidably receiving the lower end of contact rod 44, and a nozzle plate 54 having a central opening somewhat larger than contact head 48, with these two plates being secured together by a plurality (only one shown) of connecting studs 60 which are shouldered to maintain plates 52 and 54 in spaced relation, and are secured in place by screws 62. Each of the plates 52 and 54 are provided with notches 56 and 58 respectively, cut in their outer periphery, to permit relatively free passage of liquid at the outer edges of these plates. The liquid directing structure further includes a valve plate 64 located between plates 52 and 54, and being movable between nozzle plate 54 and a stop defined by shoulders 66 on studs 60. The entire liquid directing structure is biased

downwardly by a coil compression spring 68 reacting between top plate 52 and contact rod 44, with this spring being in a compressed condition at the closed circuit position due to nozzle plate 54 engaging a stop ring 69 held in place between the lower end of cylinder 28 of the interrupting chamber and a shoulder on bottom cap 30. There is also a stop washer 70 secured between contact head 40 and the lower end of contact rod 44, all for a purpose to be described.

Bottom cap 30 of the interrupting chamber is provided with a plurality of inlet openings 72 adapted to be controlled by a check valve of ring 74 freely mounted for movement between bottom cap 30 and stop ring 69. The top cap 24 of the interrupting chamber is provided with a hollow chamber 76 having an opening at one side as at 78, and also communicating with the interior of the interrupting chamber as by outlet openings 80 provided in the inner wall of top cap 24. The outlet openings 80 are adapted to be controlled by a valve ring 82, preferably biased to a position away from openings 80 by a plurality of coil compression springs 84 (only one of which is shown).

The structure of interrupting chamber 26 and its operation is similar to that disclosed and claimed in the patent of J. M. Wallace, No. 2,528,197, which issued on October 31, 1950, entitled Circuit Interrupters, and is assigned to the same assignee as this invention. Accordingly, reference is hereby made to such copending application for a more detailed description of the construction and operation of this type of interrupting device. In general, when contact rod 44 is moved upwardly, an arc will be struck between the contact tips 34 and 50, and since the interrupting chamber is filled with an arc extinguishing liquid such as oil, being submerged in container 2 which is filled with such liquid up to level L, the arc will decompose the oil and generate gas within the interrupting chamber. This will cause an internal pressure which will seat valve rings 74 and 82 on the inlet and outlet openings, respectively. This internal pressure will also act on contact rod 44 and its sheath 46 in a piston-like manner to accelerate its movement away from fixed contact tip 50. The liquid directing structure does not move during initial upward movement of contact rod 44 because it is held in engagement with stop ring 69 by spring 68. However, when contact rod 44 has moved upwardly an amount sufficient that stop washer 70 engages plate 52, the entire liquid directing structure will then be pulled upwardly with the contact rod, and liquid will be forced from the upper part of the interrupting chamber around the outer edge of plate 52 and through the central opening in nozzle plate 54 to provide a blast of liquid through the arc in a generally longitudinal direction. After contact rod 44 has moved upwardly an amount sufficient to extinguish the arc, the pressure within interrupting chamber 26 will decrease and permit valve ring 82 to uncover outlet openings 80 and thus permit escape of gases from the interrupting chamber through outlet openings 80, hollow chamber 76, and openings 78 to be discharged at one side of the top cap 24 for the interrupting chamber. Gases which thus escape from the interrupting chamber are replaced by fresh liquid flowing into the bottom of the interrupting chamber through inlet opening 72 which displaces valve ring 74 upwardly. While the gen-

eral structure and operation is thus very similar to that disclosed in the above-mentioned copending application of J. M. Wallace, it will be observed that one difference resides in the method of exhausting gases from the interrupting chamber due to the novel construction of top cap 24. In the case of an automatic reclosing circuit breaker which starts to reclose as soon as the circuit has been interrupted, the flushing out of gases and replacement of liquid within the interrupting chamber is facilitated during downward movement of contact rod 44 and the liquid directing structure by valve plate 64 which is free to move upwardly and thus uncover the openings around the outer edge of nozzle plate 54, so that the flushing operation is thus relatively unimpeded, as compared to the restricted path for flow of fluid through the liquid directing structure when the contacts separate.

In order to automatically open the contacts in response to overloads on the circuit, it will be observed that the movable contact rod is connected by a conductor 86 to one terminal of solenoid coil 20 and this, in turn, is connected by a conductor 88 to the other terminal bushing 40 on cover casting 8 (not shown). The solenoid coil 20 is thus connected in series with the circuit through contact tips 34 and 50. A solenoid core 90 in the form of a tube is slidably mounted on contact rod 44, being of a magnetic material such as iron. The upper end of solenoid core 90 is slidably received in a collar 92 secured between supporting plate 18 and the bottom of the solenoid coil 20. The solenoid coil is annular in form and has a central opening receiving a dashpot sleeve 94 of insulating material, such as fiber or a molded insulating material. An actuating tube 96 of a non-magnetic material such as brass or the like, has its lower end secured in the lower end of solenoid core 90 and it extends upwardly through solenoid coil 20 being provided with a collar 97 resting on the top surface of casting 14. A coil compression spring 98 is received within actuating tube 96 and reacts at its lower end against a collar 95 secured in the lower end of tube 96 and at its upper end engages an abutment (not shown) on contact rod 44.

Casting 14 is also of a hollow construction as seen in Figure 3, with the hollow chamber 100 formed within this casing communicating with the upper end of dashpot sleeve 94, and having an opening at one side which may be closed by a plug 102. However, if desired, plug 102 may be removed and the opening from chamber 100 will then be controlled by a piston valve member 104 vertically slidably movable in a counting cylinder 106 mounted in casting 14. The lower end of counting cylinder 106 is closed by a plug having an opening controlled by a ball-check valve 108 to permit liquid to enter the lower end of the cylinder but preventing it from escaping therefrom. Piston valve 104 is provided with a stem 110 at its upper end which has a plurality of annular ratchet flanges 112 formed thereon in spaced relation, for engagement by a pawl 114 pivotally mounted as at 121 on a lever 116 having a split outer end located at opposite sides of contact rod 44, and resting on collar 97 of actuating sleeve 96. Lever 116 is pivotally mounted on casting 14 at 117, and is normally biased counterclockwise to keep the outer end in engagement with collar 97 by a coil tension spring 118 secured between lever

116 and a lug 119 integral with casting 14. Pawl 114 is biased in a counterclockwise direction relative to lever 116 by a spring 120, to maintain a nose 122 of the pawl in engagement with the underside of lever 116.

The particular construction of casting 14 and parts associated therewith described above is similar to that disclosed and claimed in the copending application of J. M. Wallace et al., Serial No. 719,524, filed December 31, 1946, on Circuit Interrupters, now Patent No. 2,626,329 issued January 20, 1953, and assigned to the same assignee as this invention. Accordingly, for a more complete disclosure of the construction and operation thereof, reference is hereby made to the copending application of J. M. Wallace et al. Generally speaking, the operation of interrupting the circuit, when solenoid coil 20 becomes energized sufficiently to move core 90 upwardly, is that the core first moves upwardly displacing liquid in dashpot sleeve 94 upwardly into casting 14, and if plug 102 is in place the liquid can escape only by way of the relatively small clearance between core 90 and collar 92 so that the upward movement of the core will thus be slowed down by this dashpot action. However, if plug 102 is not in place, the liquid will be freely discharged from chamber 100 in casting 14, and solenoid core 90 will not be restrained in its upward movement, at least on a first circuit interrupting operation in any series of closely successive circuit interrupting operations. Upward movement of core 90, of course, carries actuating sleeve 96 and its collar 97 upwardly, and this moves lever 116 upwardly to carry pawl 114 into engagement with the uppermost ratchet flange 112 on piston 104 to carry the piston upwardly a predetermined amount. Upward movement of core 90 also will ultimately compress spring 98 sufficiently to cause upward movement of contact rod 44, to thus establish an arc and interrupt the circuit in the manner previously described. After a circuit interruption, core 90 and contact rod 44 are free to descend together to close the circuit, except that, if plug 102 of casting 14 is in place, this descent will be slowed down by the necessity of replacing liquid within the upper part of dashpot sleeve 94 through the relatively small clearance between the core 90 and collar 92. If upon reclosing of the circuit breaker contacts the overload still persists the contacts will immediately be reopened in the same manner except that this time counter piston 104 will be advanced a further amount to a position where it closes the opening from chamber 100, so that the second closing operation will be slowed down by the dashpot action of core 90 in sleeve 94, even though plug 102 is not in place. On a third closely successive circuit opening operation the upward movement of core 90 will be slowed down by the dashpot action of sleeve 94, even though plug 102 is not in place, because piston valve 104 will still be at a position where it closes off the opening from chamber 100 of casting 14. While piston 104 is biased by gravity to reset to its original position, this action is very slow due to the necessity of displacing liquid trapped beneath the piston through the relatively small clearance between the piston and cylinder 106, with the result that piston 104 does not have time to reset where circuit interrupting operations occur in rapid succession.

The upper end of contact rod 44 is connected by a pair of insulating links 124, of fiber or the like, to the common pivot 126 of a pair of links

128 and 130. Link 130 is biased to the left as viewed in Fig. 1 by a coil tension spring 132 connecting link 130 and cover casting 8. However, since link 128, which is of inverted channel form having side flanges 135 (only one of which is shown), has its other end pivoted on a bracket 136 supported from cover casting 8 as by screws 138, and since link 130 has an integral hook 134 which extends through an opening in the bight portion of link 128, the result is that spring 132 biases link 128 in a clockwise direction, to thus bias contact rod 44 downwardly to exert pressure causing pressure engagement of contact tips 50 and 54.

There is also provided within cover casting 8 a pair of toggle levers 140 and 142 connected by a center pivot 144. Toggle lever 142 has its other end slotted to receive a fixed pin 148 mounted in cover casting 8, while toggle lever 140 is mounted on a fixed pivot 146 and extends out through an opening in the cover casting beneath a hood portion 145 to form a handle extension 152 having a hook-eye 156 in the outer end thereof for manual operation. A coil compression spring 150 is telescoped over toggle lever 142 thus pushing this lever and center pivot 144 to the left as viewed in Figure 1, so that at the position of the parts illustrated, with center pivot 144 located beneath a line extending from fixed pivot 146 to pin 148, the handle extension 152 of lever 140 is maintained in engagement with a stop screw 154 beneath hood 145.

The spring arrangement and mechanism mounted within cover casting 8 is identical with that disclosed in the copending application of H. L. Rawlins et al., Serial No. 719,572, filed December 31, 1946, on Circuit Interrupters, now Patent No. 2,622,167 issued December 16, 1952, and assigned to the same assignee as this invention. Accordingly, for a more complete description of the structure and operation of these parts, reference is hereby made to the Rawlins et al. application. In general, the operation of these parts during a circuit opening operation is such that initial upward movement of contact rod 44 during a circuit opening operation results in levers 128 and 130 approaching each other to thus reduce the force component of spring 132 which biases contact rod 44 downwardly, until the end of spring 132 connected to lever 130 substantially coincides with the pivot mounting of lever 128 on bracket 136. At this time, spring 132 will have substantially no force component in a downward direction, and accordingly, contact rod 44 is not opposed by spring 132 in its further upward movement. It will be apparent that when the circuit is interrupted, thus freeing contact rod 44 for downward movement which may or may not be impeded by the dashpot action of solenoid core 90 in dashpot sleeve 94 as previously pointed out, that the parts will move downward initially due to the force of gravity, until the point is reached where links 128 and 130 begin to separate, and thus establish a downward component of spring 132, to accordingly increase the speed at which final engagement of the contacts occurs and, of course, finally establish a contact pressure, as previously pointed out.

Handle extension 152 of toggle lever 140 may, of course, be moved downwardly to move center pivot 144 upwardly overcenter, to thus release spring 150. The center pivot pin 144 has an extension beneath the adjacent flange 135 of link 128, so that upward movement of this center pin carries link 128 with it, and consequently,

raises contact rod 44 to open the circuit breaker contacts. Such manual opening of the circuit breaker contacts is, of course, accelerated by spring 150 as soon as pivot 144 passes overcenter, and the circuit breaker contacts are maintained open by spring 150. After such a manual operation the circuit breaker may be manually closed by moving handle extension 152 upwardly, and thus permitting contact rod 44 to move downwardly in the manner previously described.

Toggle lever 142 is provided with an extension 158 which overlies an extension 160 of insulating material, such as fiber or a molded insulating material, mounted on the upper end of stem 118 of piston 104. The purpose of this is to lock the circuit breaker contacts open after a predetermined number of closely successive circuit interrupting operations have occurred. Thus, as previously pointed out, piston 104 will be advanced a predetermined amount on each circuit opening operation, and if these operations occur in close succession, the piston will eventually be advanced an amount sufficient to cause its extension 160 to engage extension 158 of toggle lever 142, and move pivot 144 overcenter, to thus cause opening of the contacts by spring 150 in the manner previously described, and this spring, of course, will then hold the contacts at an open circuit position.

It will be observed that both circuit opening and circuit closing operations may be controlled by the dashpot action of solenoid core 90 in dashpot sleeve 94, with this operation during a circuit interruption displacing liquid trapped in the upper part of dashpot sleeve 94 out through the narrow clearance between core 90 and collar 92. During a circuit closing operation, the reverse flow of fluid occurs, because fluid must then be supplied to the upper part of dashpot sleeve 94 through the same narrow clearance. In prior devices where the gases evolved during a circuit interrupting operation were released at a point beneath dashpot sleeve 94, such gases in passing upwardly in container 2 often found their way into dashpot sleeve 94 thus causing erratic operation thereof both in circuit opening and circuit closing operations. It will be observed that this can not happen with the construction comprising this invention, because the gases generated during circuit interruption are released at one side, through side opening 78 from chamber 76 in top cap 24 of the interrupting chamber 26, so that in proceeding upwardly these gases will follow a path laterally spaced from the lower end of dashpot sleeve 94. Moreover, top cap 24 of the interrupter chamber is formed to provide a gas baffle or separator which prevents escape of gases to the top of cap 24 through the clearance between sleeve 46 and the central opening in cap 24. This is due to the fact that sleeve 46 passes through two walls of top cap 24, and that chamber 76 is formed between these two walls. Thus, while a high pressure may exist within the chamber during circuit interruption which may force gas through the clearance between sleeve 46 and the central opening of the inner wall of top cap 24, this gas arrives in chamber 76, and there being no pressure differential between this chamber and the top side of cap 24, but actually chamber 76 being liberally vented at opening 78, gas arriving in the chamber will be free to move laterally through it and escape from this side opening 78 which provides an effective gas directing means. Thus, no gas will appear above the top of cover cap 24, and to make sure that

gas bubbling upwardly from side opening 78 does not deviate inwardly, a tubular shield 162 of insulating material, preferably a molded insulating material, is placed immediately above top cap 24, being supported from supporting plate 18 by means of brackets 164 which may be welded thereto and secured to shield 162 as by screws 166. Gases escaping from interrupting chamber 26 are thus at all times prevented from reaching

10 the dashpot liquid inlet or intake at the lower ends of dashpot sleeve 94 and collar 92, so that no improper operation of the dashpot can result. Conductor 86 extends through a vertical slot 87 in shield 162 at the side opposite gas outlet 78.

An additional precaution is taken where the dashpot action during a circuit closing operation is made to be different than that during a circuit opening operation, as illustrated in Fig. 3, 20 by the provision of an additional inlet for fluid into the upper part of dashpot sleeve 94 during descent of core 90. This is provided in the underside of casting 14 which has a tapped opening for threaded receiving a plug 168 which is 25 hollow and has a small opening extending through an intake extension 172 of reduced area, and controlled by a ball-check valve 170. The plug 168 has an integral relatively large sleeve 174 which is closed at its lower end by a closure disk 176 to form a sump chamber having an inlet from the interior of tank 2 formed by a slot 178 at the top of this sump chamber. During a circuit closing operation, ball-check valve 170 will be unseated to permit additional 35 flow of liquid inwardly through the plug 168, and if there is any gas in the vicinity of the intake, there will be no tendency for it to accumulate at the bottom of the sump because the rate of oil flow into chamber 100 of casting 14 is small compared to the size of the sump, and, consequently, 40 a supply of clear oil is maintained under check valve 170, and any gas bubbles in container 2 will rise past slot 178, there being no tendency for them to enter the sump formed in the bottom of plug 168.

45 It is believed apparent from the foregoing that this invention provides an arrangement for circuit breakers which have one or more of their operations controlled by liquid time delay means, 50 such as a dashpot, whereby gases formed by action of the arc on the liquid employed in the circuit breaker, are positively prevented from interfering with the operation of such time delay means. Important features of this construction comprise confining the escape of such gases 55 to a position at one side of the circuit breaker at a point laterally displaced from the liquid intake of the time delay means, and the provision of baffles to prevent such gases from affecting the time delay means.

Having described a preferred embodiment of the invention, in accordance with the patent statutes, it is desired that the invention be not limited to the particular constructions described 65 herein, inasmuch as it will be apparent to persons skilled in the art that many changes and modifications may be made in these particular constructions without departing from the broad spirit and scope of the invention. Thus, it is 70 apparent that the invention need not be employed with circuit breakers of the automatic reclosing type although it has certain novel features of cooperation with this type of circuit breaker, but may be employed in any type of circuit breaker having one or more operations there-

of controlled by liquid time delay means. Also, the gas separating means herein disclosed may be employed separately or in various combinations thereof. Accordingly, it is desired that the invention be interpreted as broadly as possible and be limited only as required by the prior art.

We claim as our invention:

1. A circuit breaker comprising, a container for an arc extinguishing liquid, separable contacts mounted in said container beneath the liquid level thereof, means responsive to a predetermined condition of the circuit for separating said contacts to interrupt the circuit, liquid time delay means controlling the operation of said condition responsive means and also located in said container, said time delay means having a liquid inlet positioned below the liquid level in said container so that it will employ said arc extinguishing liquid in operation, and gas baffle means in said container below the liquid level thereof for preventing gases generated by the arc formed during separation of said contacts from entering the liquid inlet of said time delay means.

2. A circuit breaker comprising, a container for an arc extinguishing liquid, separable contacts mounted in said container beneath the liquid level thereof, means responsive to a predetermined condition of the circuit for separating said contacts to interrupt the circuit, liquid time delay means controlling the operation of said condition responsive means and also located in said container, said time delay means having a liquid inlet positioned below the liquid level in said container so that it will employ said arc extinguishing liquid in operation, and gas baffle means in said container below the liquid level thereof and positioned adjacent said liquid inlet for preventing gases generated by the arc formed during separation of said contacts from entering the liquid inlet of said time delay means.

3. A circuit breaker comprising, a container for an arc extinguishing liquid, separable contacts mounted in an arc chamber located within said container beneath the liquid level thereof, means responsive to a predetermined condition of the circuit for separating said contacts to interrupt the circuit, liquid time delay means controlling the operation of said condition responsive means and also located in said container, said time delay means having a liquid inlet positioned below the liquid level in said container so that it will employ said arc extinguishing liquid in operation, said chamber having an outlet for gases generated by the arc during a circuit opening operation, and gas directing means disposed adjacent to said gas outlet for directing the escaping gases away from the liquid inlet of said time delay means for preventing gases generated by the arc formed during separation of said contacts from entering the liquid inlet of said time delay means.

4. A circuit breaker comprising, a container for an arc extinguishing liquid, separable contacts mounted in an arc chamber located within said container beneath the liquid level thereof, means responsive to a predetermined condition of the circuit for separating said contacts to interrupt the circuit, liquid time delay means controlling the operation of said condition responsive means and also located in said container, said time delay means having a liquid inlet positioned below the liquid level in said container so that it will employ said arc extinguishing liquid in operation, said arc chamber having an outlet

for gases generated by the arc during a circuit opening operation, gas directing means disposed adjacent to said gas outlet for directing the escaping gases away from the liquid inlet of said time delay means, and gas baffle means in said container below the liquid level thereof for preventing gases generated by the arc formed during separation of said contacts from entering the liquid inlet of said time delay means.

5. A circuit breaker comprising, a container for an arc extinguishing liquid, separable contacts mounted in said container beneath the liquid level thereof, means responsive to a predetermined condition of the circuit for separating said contacts to interrupt the circuit, liquid time delay means controlling the operation of said condition responsive means and also located in said container, said time delay means having a liquid inlet positioned below the liquid level in said container but above said contacts so that it will employ said arc extinguishing liquid in operation, and said inlet opening to the interior of said container at one side for preventing gases generated by the arc formed during separation of said contacts from entering the liquid inlet of said time delay means.

6. A circuit breaker comprising, a container for an arc extinguishing liquid, separable contacts mounted in an arc chamber located within said container beneath the liquid level thereof, means responsive to a predetermined condition of the circuit for separating said contacts to interrupt the circuit, liquid time delay means controlling the operation of said condition responsive means and also located in said container, said time delay means having a liquid inlet positioned below the liquid level in said container but above said contacts so that it will employ said arc extinguishing liquid in operation, said arc chamber having an outlet at one side for gases generated by the arc during a circuit opening operation for preventing gases generated by the arc formed during separation of said contacts from entering the liquid inlet of said time delay means.

7. A circuit breaker comprising, a container for an arc extinguishing liquid, separable contacts mounted in an arc chamber located within said container beneath the liquid level thereof, means responsive to a predetermined condition of the circuit for separating said contacts to interrupt the circuit, liquid time delay means controlling the operation of said condition responsive means and also located in said container, said time delay means having a liquid inlet positioned below the liquid level in said container but above said contacts so that it will employ said arc extinguishing liquid in operation, said arc chamber having an outlet at one side for gases generated by the arc during a circuit opening operation, and said inlet opening to the interior of said container at one side for preventing gases generated by the arc formed during separation of said contacts from entering the liquid inlet of said time delay means.

8. An automatic reclosing circuit breaker comprising, a container for an arc extinguishing liquid, separable contacts mounted in said container beneath the liquid level thereof, means responsive to a predetermined condition of the circuit for separating said contacts to interrupt the circuit, means responsive to a circuit interrupting operation to automatically close the contacts, liquid time delay means in said container operable in opposite directions to control opening and clos-

ing of said contacts, said time delay means having a liquid inlet positioned below the liquid level in said container so that it will employ said arc extinguishing liquid in operation, and gas baffle means in said container below the liquid level thereof for preventing gases generated by the arc formed during separation of said contacts from entering the liquid inlet of said time delay means.

9. An automatic reclosing circuit breaker comprising, a container for an arc extinguishing liquid, separable contacts mounted in said container beneath the liquid level thereof, means responsive to a predetermined condition of the circuit for separating said contacts to interrupt the circuit, means responsive to a circuit interrupting operation to automatically close the contacts, liquid time delay means in said container operable in opposite directions to control opening and closing of said contacts, said time delay means having vent means through which liquid is expelled during a circuit opening operation and is taken in during a circuit closing operation, an arc chamber for said contacts which is closed at least during a circuit interrupting operation, means for venting said chamber during a circuit closing operation and gas baffle means in said container below the liquid level thereof for preventing gases vented from said arc chamber from entering the liquid inlet of said time delay means.

10. A circuit breaker comprising, a container for an arc extinguishing liquid, an arc chamber mounted in said container below the liquid level therein, separable contacts mounted in said chamber which are actuated by a rod passing through an opening in the top wall of said chamber, liquid time delay means for said rod disposed above said chamber and having a liquid inlet below the liquid level in the container so as to employ said arc extinguishing liquid in operation, the top wall of said chamber being hollow at the point where the opening for said rod is located, and a side opening communicating between said hollow space and the interior of the container to prevent gases formed during a circuit opening operation from travelling up along the rod and entering the inlet of said time delay means.

11. A circuit breaker comprising a container for an arc extinguishing liquid, an arc chamber mounted in said container below the liquid level therein, separable contacts mounted in said chamber which are actuated by a rod passing through an opening in the top wall of said chamber, liquid time delay means operable to delay movement of said rod disposed above said chamber and having a liquid inlet below the liquid level in the container so as to employ said arc extinguishing liquid in operation, the top wall of said chamber being hollow at the point where the opening for said rod is located, a side opening communicating said hollow space with the interior of the container to prevent gases formed during a circuit opening operation from travelling up along the rod and entering the inlet of said time delay means, and a cylindrical gas baffle about said rod and liquid inlet above said chamber and at a lateral distance from the rod which is less than the distance of said side opening from said rod, to thus prevent gases emanating from said opening from working inwardly toward the rod and inlet of the time delay means.

12. A circuit breaker comprising, a container for an arc extinguishing liquid, an arc chamber mounted in said container below the liquid level therein, separable contacts mounted in said

chamber which are actuated by a rod passing through an opening in the top wall of said chamber, liquid time delay means operable to delay movement of said rod disposed above said chamber and having a liquid inlet below the liquid level in the container so as to employ said arc extinguishing liquid in operation, the top wall of said chamber having a hollow space at the point where the opening for said rod is located, a side opening communicating said hollow space with the interior of the container to prevent gases formed during a circuit opening operation from travelling up along the rod and entering the inlet of said time delay means, and means for venting said chamber to said hollow space after a circuit opening operation.

13. A circuit breaker comprising, a container for an arc extinguishing liquid, an arc chamber mounted in said container below the liquid level therein, separable contacts mounted in said chamber which are actuated by a rod passing through an opening in the top wall of said chamber, liquid time delay means operable to delay movement of said rod disposed above said chamber and having a liquid inlet below the liquid level in the container so as to employ said arc extinguishing liquid in operation, a side opening in said chamber for the escape of gases therefrom formed therein during a circuit opening operation, and a cylindrical gas baffle about said rod and liquid inlet above said chamber and at a lateral distance from the rod which is less than the distance of said side opening from said rod, to thus prevent gases emanating from said opening from working inwardly toward the rod and inlet of the time delay means.

14. A circuit breaker comprising, a container for an arc extinguishing liquid, separable contacts mounted in an arc chamber located in the container beneath the liquid level thereof, means responsive to a predetermined condition of a circuit for separating said contacts to interrupt the circuit, liquid time delay means controlling the operation of said condition responsive means and also located in said container, said time delay means having a liquid inlet positioned below the liquid level in said container but above said contacts, and a chamber substantially enclosing said inlet to shield it from gases generated by an arc during contact separation, said chamber having an opening in one side to admit liquid to said chamber for supplying said inlet.

15. In a circuit interrupter, a container for an arc extinguishing liquid, separable contacts disposed in said container beneath the liquid level thereof, means responsive to a predetermined condition of a circuit for separating said contacts to interrupt the circuit, liquid time delay means controlling operation of said condition responsive means located in said container and having a liquid inlet positioned below the liquid level, and a sump chamber for maintaining a supply of the liquid for said inlet, said chamber substantially enclosing said inlet and having a relatively narrow opening on one side for admitting liquid.

16. A circuit breaker comprising, a container for an arc extinguishing liquid, separable contacts disposed in an arc chamber located within said container beneath the liquid level thereof, means responsive to a predetermined condition of a circuit for separating said contacts to interrupt the circuit, liquid time delay means controlling the operation of said condition responsive means located in said container and having

a plurality of liquid inlets, one of said inlets being disposed substantially centrally of and above the arc chamber, said arc chamber having an outlet at one side for gases generated by an arc during a circuit opening operation, and means providing a chamber about another of said openings, said chamber having a side wall with a relatively narrow opening therein for the liquid.

JAMES M. WALLACE.
